UNITED STATES PATENT OFFICE.

PAUL M. HENGSTENBERG, OF WILKINSBURG, PENNSYLVANIA, ASSIGNOR TO WESTINGHOUSE ELECTRIC & MANUFACTURING COMPANY, A CORPORATION OF PENNSYLVANIA.

TRANSFORMER.

Application filed May 26, 1923. Serial No. 641,545.

To all whom it may concern:

Be it known that I, PAUL M. HENGSTENBERG, a citizen of the United States, and a resident of Wilkinsburg, in the county of Allegheny and State of Pennsylvania, have invented a new and useful Improvement in Transformers, of which the following is a specification.

My invention relates to transformers and 10 it has particular relation to the structure thereof.

In its broadest aspect, the object of my invention is to provide a transformer structure of such design that the magnetic characteristics thereof may be very finely adjusted.

More specifically, the object of my invention is to provide a transformer particularly applicable to radiofrequency wireless 20 receiving systems and characterized by the provision of a variable air gap having a fine degree of variation whereby the degree of regeneration of said radio receiving system may be selectively controlled.

With these and other objects and applications in mind, my invention further consists in the details of construction and arrangement which will appear more fully hereinafter in connection with the accompanying 30 description, claims and drawings, wherein,

Figure 1 is a view, partially in front elevation and partially in section, of one embodiment of my invention.

Fig. 2 is a horizontal sectional view of the structure shown in Fig. 1 taken on line 35 II-II thereof.

Figs. 3 and 4 are front and side elevational views, respectively, of the element designed to bind together the punchings of the transformer core and to resiliently support the same.

Fig. 5 is a view of the punched metal blank from which the element of Figs. 3 and 45 4 is formed.

In the illustrated form of embodiment of my invention shown in Fig. 1, I provide a pair of magnetic yoke members 1 and 2 of substantially U shape, which are built up of punchings of sheet iron of high grade or preferably of silicon steel. In order to keep core losses small, the laminations are made as thin as can be readily manufactured and

insulated by enamel or in any other suitable manner. The two yoke members have 55 the middle portions 3 and 4 respectively and each yoke member has arms extending toward the other so that the yoke 1 has arms 5 and 6 and the yoke 2 arms 7 and 8. Thus the arms 5 and 7 afford a pair of proximate ends and the arms 6 and 8 another pair.

The punchings of the yoke members 1 and 2 are secured together by the clamping elements 14 and 15, respectively. These elements and also the yoke members 1 and 2 are flexibly supported by extensions 16 and 17 of the elements 14 and 15, respectively, which are secured to the base plate 18 in such manner that the said proximate ends of the yoke members 1 and 2 face each other, thereby forming a closed magnetic circuit having variable air gaps 19 and 21 therein. One pair of proximate ends of the yoke members 1 and 2 may be provided with 75 bakelite rings 22 serving to securely bind together the punchings. A micarta tube 23 is positioned to embrace the other pair of proximate ends of the yoke members 1 and 2 and serves to provide a support for spaced 80 transformer windings 24 and 25.

The previously mentioned clamping elements 14 and 15 may be originally constructed from a blank 26, of the shape shown in Fig. 5, preferably made from phosphor bronze by punching. The blank 26 comprises a longitudinally extending body 27 designed to engage the end surface of one of said yoke members, and side portions 28 and 29 adapted to be bent to engage, respectively, the opposite faces of the middle portions of a yoke member. At one end, said side portions are cut along the lines of the bends to provide portions 31 and 32 adapted to be bent transversely of said bent side portions 28 and 29 to engage the lower arm of said yoke member.

At the other end, said side portions 28 and 29 are cut for a distance intermediate the lines of the bends *a* and *b* and the outer edges of said side portions to provide portions 33 and 34 adapted to be transversely bent to engage the upper arm of said yoke member. The body section 27, which is positioned intermediate the side portions 31 and 32, is so cut as to provide a resilient

tongue or spring member 35 which is integral therewith. A portion 36 of the body section 27 and the portions 37 and 38, which remain between the sections 34 and 33 and 5 the lines of the bends *a* and *b*, respectively, are adapted to be bent to form a recess for a spring member 39, as shown in Fig. 1. The opposite end of the body section 27 is provided with the extension 16 adapted to 10 be bent along a dotted line *c* to provide a supporting foot 40, whereby the previously mentioned sections may be resiliently supported. The foot 40 may be rendered more rigid, by bending the same back on itself 15 along a line *c'* as shown in Fig. 1.

In order to form the element 14, which is shown in Figs. 1, 3 and 4, from the punching 26, which is shown in Fig. 5, the longitudinally extending body 27 is first positioned in engagement with the outer surface of the middle portion 3 of the yoke member 2 and the side portions 28 and 29 bent to engage the opposite faces thereof. The sections 31 and 32 are next transversely bent to engage the lower surface of the arm 6 of the yoke member 2 and the binding of the core laminations constituting the same is completed by the bending of the sections 33 and 34 to contact the upper surface of the arm 5. It is noted that the several sections just mentioned form, in effect, a cup which rigidly binds together the punchings of the yoke member 2. The extension 16 is then transversely bent along the dotted line *c* to provide a supporting foot 40 which is bent a second time at *c'* and secured to the base member 18, thereby providing a resilient support for the yoke member 1. The tongue 35 which is provided in the body 27, is then bent outwardly to form a spring member, as shown in the drawing. The laminations of the remaining yoke member 2 are similarly bound together and this yoke member is resiliently supported by the element 15 which is a duplicate of the element 14, just described.

A cylindrical casing 41 which has one end closed by the supporting plate 18 serves as an additional support for the transformer and also engages the spring tongue 35. These tongues project so far that if they were unopposed the proximate ends of the U shape yoke members 1 and 2 would be actuated into engagement with each other, and the air gaps 19 and 21 would be closed. The spacing of the proximate ends, may however, be adjusted by means of the leaf spring 39 which has opposite ends seated in the recesses formed by the end sections 36, 37 and 38 of the elements 14 and 15, all as shown in the drawing.

The remaining open end of the casing, which is just beyond the leaf spring 39, may be closed by a plate 42 which is rigidly secured to the oppositely positioned plate

18 by means of tie rods 43. The plate 42 is provided with a threaded perforation 44 directly over the leaf spring 39, whereby a screw member 45 may be adjustably moved into engagement with the leaf spring member 39 to vary the force thereof tending to overcome that of the tongues 35, whereby the relative spacing of the proximate ends of said yoke members may be varied.

In operation, with the apparatus in the 75 position shown in Fig. 1 of the drawings, when the screw member 45 is so turned as to increase the pressure thereof on the leaf spring 39, the force of the latter tending to separate the proximate ends of the yoke 80 members 1 and 2 gradually become greater than the force of the tongue members 35 tending to maintain said ends in engagement and the ends, therefore, are separated,—the reverse obtaining as the adjusting screw 45 is withdrawn from engagement 85 with the spring member 39.

While I have described a specific embodiment of my invention in great detail, and while I have pointed out certain of the most 90 obvious principles and purposes thereof, I do not intend that the language employed in the following claims shall be limited to the precise features described but I intend that the claims shall be construed to cover 95 all combinations which are included in the claims, when read in connection with the prior art, regardless of the details and functions mentioned in the description or illustrated in the drawing.

I claim as my invention:

1. A transformer core comprising individual portions having proximately disposed ends, means for resiliently mounting said individual portions in such manner that the spacing of said proximate ends may be varied, said means exerting a resilient force on said individual portions tending to maintain said concurrent ends in a predetermined spaced relation and controlling means for exerting a resilient force on said individual portions opposing said mounting means, whereby the spacing of said concurrent ends may be controlled.

2. A transformer core comprising a pair 115 of separate portions, each portion having arms, corresponding arms of the respective portions being adjacently disposed, means for resiliently positioning said portions in a predetermined position and additional resilient means for adjusting the spacing of said co-operating arms.

3. A transformer core comprising a pair of magnetic yoke members having pole terminals, a supporting structure, resilient means co-operating with said supporting structure and said yoke members for flexibly mounting the pole terminals of one yoke member adjacent to the pole terminals of the other yoke member, additional means 125 130

for resiliently adjusting the spacing of said adjacent pole terminals, and primary and secondary windings on said core.

4. A transformer comprising a pair of laminated yoke members having adjacently positioned pole terminals, individual means for binding the laminations of each yoke member, a supporting member, said individual means having extensions for so flexibly mounting said yoke member on said supporting member that the spacing of said adjacently positioned pole terminals may be varied, additional supporting means, resilient means for engaging said additional supporting means to position said yoke member, causing the spacing of said pole terminals to assume a predetermined value, and adjustable means for, at will, overcoming the force of said last-mentioned resilient means, whereby the spacing of said pole terminals may be varied.

5. In combination, a laminated yoke member, a casing having opposite ends, one of said ends being closed, and integral means for binding the lamination of said yoke member and for so mounting said yoke member on said closed end as to provide for motion transverse to said casing, said means also having a flexible extension bearing against the wall of said casing and serving to bias said member toward one limit of said transverse motion.

6. A blank having a body and a pair of side sections adapted to be bent into position to bind the lamination of a yoke member; the body of said blank being so cut as to provide a resilient tongue, said body having a longitudinal extension adapted to be bent to provide a resilient supporting section for said blank.

7. A blank having a body and a pair of side sections adapted to be bent into position to bind the laminations of a yoke member, the body of said blank being so cut as to provide a resilient tongue, the body of said blank being oppositely extended to provide, respectively, a resilient supporting section and a spring receiving recess.

8. A blank comprising a body section having side portions positioned intermediate the ends of said body section and adapted to rigidly embrace a yoke member, said section also being cut in such manner as to provide an integral resilient spring member, one end of said blank serving as a support adapted to resiliently mount said yoke member, and the other end adapted to serve as a stop-member for an adjusting spring.

9. A blank comprising a longitudinally extending section having offset portions adapted to be transversely bent to engage, respectively, the opposite faces of a core member, one end of said offset portions being cut along the lines of the bends to provide portions adapted to be bent transverse-

ly of said bent offset portions to engage one side of said core member, the remaining ends of said off-set portions being cut intermediate the lines of the bends and the outer edges of said offset portions to provide portions adapted to similarly engage the other side of said core member, the end of said longitudinally extending section being adapted to serve as a supporting section.

10. A blank comprising a longitudinally extending section having side portions adapted to be bent to engage the opposite faces of a core member, said side portions being cut at one end along the lines of the bends to provide portions adapted to be bent to engage one side of said core member, the other ends of said off-set portions being cut intermediate the lines of the bends and the outer edges of said portions to provide portions adapted to be bent to engage another side of said core member, said blank also being so cut as to provide a resilient tongue section intermediate said side portions.

11. A blank comprising a longitudinally extending body having side portions adapted to be bent to engage the opposite faces of a core member, said side portions being cut at one end along the lines of the bends to provide portions adapted to engage one side of said core member, the other ends of said side portions being cut intermediate the lines of the bends and the outer edges of said portions to provide portions adapted to be bent to engage another side of said core member, said blank being so cut as to provide a resilient tongue section intermediate said side portions and said body being extended to provide a resilient supporting section.

12. A transformer core comprising a pair of yoke members of U-shape, a supporting plate, a tubular casing carried by said plate, means for flexibly mounting said yoke members on said plate in such manner that the ends thereof face one another in spaced relation, means integral with said mounting means for engaging said casing to resiliently resist variation in the spacing of said facing ends, a spring member and means integral with said mounting means and co-operating with said spring to partially balance the force of said second-mentioned means.

13. A transformer core comprising a pair of members of U-shape, a supporting plate, a tubular casing carried by said plate, means for flexibly mounting said members on said plate in such manner that the ends thereof face one another in spaced relation, means integral with said mounting means for engaging said casing to resiliently resist variation in the spacing of said facing ends, a spring member, means integral with said first-mentioned means providing a seat for said spring, whereby the force thereof may partially balance that of said second-mentioned means, a closure for the remaining

end of said casing and means carried by said closure for regulating the force of said spring member.

14. A transformer core comprising a pair of members of U-shape, a supporting plate, a tubular casing carried by said plate, means for flexibly mounting said members on said plate in such manner that the ends thereof face one another in spaced relation, spring members extending from said mounting means and engaging said casing, whereby said spring members tend to hold said ends in engagement, a resilient member, said first-mentioned means being provided with an extension adapted to co-operate with said resilient member to oppose said spring members, a closure for the remaining end of said casing and means carried by said closure for operating on said resilient member to vary the spacing of said ends.

15. A transformer core comprising a pair of members of U-shape, a supporting plate, a tubular casing carried by said plate, means for flexibly mounting said members on said supporting plate in such manner that the ends thereof face one another, spring members extending from said first-mentioned

means and engaging said casing, whereby said spring members tend to hold said ends in engagement, a resilient member, said first-mentioned means being provided with an extension adapted to co-operate with said resilient member to resist the force of said spring members, a closure for the remaining end of said casing, said closure being provided with a threaded perforation, and a screw member extending therethrough and engaging said resilient member, whereby the spacing of said ends may be adjustably controlled.

16. A transformer core comprising a pair of separate portions, each portion having a face opposite the corresponding face of the other, said opposite faces being separated to provide an air gap, means tending to move said portions toward each other and adjustable means for opposing said first named means, whereby the length of the air gap is controlled.

In testimony whereof, I have hereunto subscribed my name this 21st day of May, 1923.

PAUL M. HENGSTENBERG.
